(57) **CLAIM**

The ornamental design for an attachment base as shown and described.

DESCRIPTION

FIG. 1 is a bottom view of an attachment base showing my new design;

FIG. 2 is a top-down view of a decorative element attached to the attachment base from the embodiment shown in FIG. 1;

FIG. 3 is a right-side view of the attachment base from the embodiment shown in FIG. 1;

FIG. 4 is a left side view of the attachment base from the embodiment shown in FIG. 1;

FIG. 5 is a front side view of the attachment base of the embodiment shown in FIG. 1;

FIG. 6 is a back side of the attachment base of the embodiment shown in FIG. 1;

FIG. 7 side perspective view of the attachment base of the embodiment shown in FIG. 1; and,

FIG. 8 is a bottom-up perspective view of the attachment base of the embodiment shown in FIG. 1.

The solid hatching of the figure drawings is included to illustrate the surface of the attachment base. The solid hatching has no bearing on texture, finish, etc. The broken lines form no part of the claimed design.
